WO WO2014164744 10/2014

Primary Examiner — Terry A Wallace

(57) **CLAIM**

The ornamental design for a beverage can insulation sleeve, as shown and described.

DESCRIPTION

FIG. 1 is a front view of a beverage can insulation sleeve showing my new

FIG. 2 is a rear view of the beverage can insulation sleeve; FIG. 3 is a right side view of the beverage can insulation sleeve;

FIG. 4 is a left side view of the beverage can insulation sleeve;

FIG. 5 is a top view of the beverage can insulation sleeve; FIG. 6 is a bottom view of the beverage can insulation sleeve;

FIG. 7 is a top front side perspective view of the beverage can insulation sleeve; and,

FIG. 8 is a top front side perspective view of the beverage can insulation sleeve in use.

The broken lines in FIG. 8 are illustrative of environmental structure forming no part of the claimed design.

1 Claim, 8 Drawing Sheets
